THERMOSTATIC AQUARIUM HEATER

Henry M. Arak, 2480 Ocean Parkway,
Brooklyn, N.Y. 11235

Filed Feb. 25, 1965, Ser. No. 83,999

Term of patent 14 years

(Cl. D81—2)

FIG. 1 is a front perspective view taken from one side of a thermostatic aquarium heater embodying my new design;

FIG. 2 is a fragmentary side view thereof;

FIG. 3 is a top view thereof;

FIG. 4 is a fragmentary front view thereof;

FIG. 5 is a fragmentary rear view thereof; and

FIG. 6 is a view similar to FIG. 1, but showing the lid thereof in raised position.

I claim:

The ornamental design for a thermostatic aquarium heater, substantially as shown.
